US0D1017664S

(12) **United States Design Patent** (10) **Patent No.:** **US D1,017,664 S**
(45) **Date of Patent:** **** Mar. 12, 2024**

(54) **CAMERA**

(71) Applicant: **Shenzhen General Technology Co. Ltd**, Shenzhen (CN)

(72) Inventor: **Shuai Jiang**, Shangqiu (CN)

(73) Assignee: **Shenzhen General Technology Co. Ltd**, Shenzhen (CN)

(**) Term: **15 Years**

(21) Appl. No.: **29/839,018**

(22) Filed: **May 17, 2022**

(51) LOC (14) Cl. **16-01**

(52) U.S. Cl.

USPC **D16/203**
